PUNCH EJECTOR DIE

Samuel Singer, Philadelphia, Pa.

Application December 30, 1933, Serial No. 704,692

1 Claim. (Cl. 164—124)

My invention relates to punch ejector dies. The object is to provide a die so formed as to facilitate the discharge of the cuttings without the possibility of clogging.

5 The invention comprises a hollow punching die associated with a supporting element having a channel in communication with the passage through the die, said channel being so formed and disposed as to receive the cuttings from the die and to discharge said cuttings without possibility of clogging.

Referring to the drawing, which illustrates merely by way of example suitable means for the embodiment of my invention:—

15 Fig. 1 is a view in perspective of the die and supporting block.

Fig. 2 is a vertical section of the same.

Fig. 3 is a fragmentary section showing, more or less diagrammatically, the method of operation.

Similar numerals refer to similar parts throughout the several views.

In the example shown, the block 5 is of rectangular form provided with a boss 6 having a bore 7 for receiving the die 8 which is hollow; the interior walls of the die tapering from the base to the outer cutting edge 9. The die is secured within the bore 7, in any well known way, with its base abutting the annular flange 10. Beyond the flange 10 a channel 11 is provided in the block. This channel extends longitudinally with straight, substantially parallel side walls and curved end walls. The upper end wall 12 extends above or beyond the margin of opening 13 in flanged part 10 of the block, for the purpose herein to be described. Between the boss 6 and the lower end wall 14 is provided the discharge opening 15.

The device comprising the die with its supporting block, is adapted to be mounted and operated in the usual way in connection with a suitable press.

In operation the material such as card board, leather, or the like, sheets are punched by being pressed against the cutting edge 9 of the die 8. The cuttings or wads 16 accumulate in the bore of the die and move progressively toward the passage 13 in the annular flange 10, with each successive punching operation. The pressure created by each successive cutting or wad that enters the die and is crowded upon those in advance of it, will tend to compact the cuttings so that, as the same pass through the opening 13, some of the cuttings may adhere together and the advance

cutting will not immediately fall and be discharged, after passing the opening 13.

In order to prevent the clogging of the cuttings and to assure their free discharge it has been proposed to provide some deflecting means immediately at the discharge end of the die opening, but it has been found that, due to the cutting adhering together or, for other reasons, such deflecting means tends to obstruct the forward movement of the cuttings and thus to increase 10 the tendency to clog.

To overcome this difficulty as well as others, I have found that the discharging operation is facilitated by providing a substantial space or clearance between the top of end wall 12 of the channel 11, and the margin of the discharge opening, such as 13, combined with the curved formation of the top wall as at 12. In the first place the cutting, after passing the margin of orifice 13, is free to fall immediately, if not adherent to 20 an adjacent cutting, because it has encountered no obstruction.

If, on the contrary, the cuttings should adhere or stick together, they will, as they advance, encounter the smoothly curved top wall 12. By 25 cause of this engagement, there is created a force acting upon the advancing cuttings, which is inclined to the original path of their travel. Thus the cuttings are caused to slide one upon another, and automatically separate from each other, to 30 be discharged through opening 15, as indicated in Fig. 3.

It is especially important, whether the cuttings separated freely or not, that the cutting shall not encounter any obstacle to its forward movement, until it has entirely cleared the margin of the opening 13, since otherwise the free passage of the cuttings through the die is obstructed. For this reason the top of the upper curved wall 12 is carried well above and spaced from the margin 35 of the annular flange 10.

What I claim is:—

The combination of a block having a boss at one end thereof and projecting above the main body of the block, said block provided with a longitudinally extending channel having an outwardly curved wall at each end, the boss provided with a bore having its axis at right angles with the longitudinal extension of the channel, an annular flange formed between the bore and the 45 channel, and a cylindrical die fitted into the bore and abutting the annular flange.

SAMUEL SINGER.
